UNITED STATES PATENT OFFICE.

EDWARD E. RICE, OF NEW DURHAM, NEW HAMPSHIRE, ASSIGNOR TO THE OSBORN MANUFACTURING COMPANY, OF CLEVELAND, OHIO, A CORPORATION OF OHIO.

BRUSH.

No. 894,053.

Specification of Letters Patent.

Patented July 21, 1908.

Application filed November 20, 1907. Serial No. 402,971.

To all whom it may concern:

Be it known that I, EDWARD E. RICE, a citizen of the United States, resident of New Durham, county of Stafford, and State of New Hampshire, have invented a new and useful Improvement in Brushes, of which the following is a specification, the principle of the invention being herein explained and the best mode in which I have contemplated applying that principle so as to distinguish it from other inventions.

The present invention relates to the construction or manufacture of brushes, and particularly to brushes in which metal strands or wires are utilized in forming the bristles or tufts of bristles that make up the body of the brush. Brushes thus constructed are especially adapted and largely used for removing the sand from the surfaces of new iron castings. As is well understood the desiderata in the construction of brushes of this character are a reduction of the vibrations that are set up among the strands when the brush is in use and a transfer of the center of such vibration, in the case of the individual strand, from its point of attachment to the back of the brush to a lower point along the strand. This may be more simply expressed by stating that it is desirable that the strand be bent more or less uniformly throughout its length instead of vibrating simply at its point of attachment to the back. The effect of such vibration, in the case of a metal strand at least, is very quickly to cause the metal to crystallize or become brittle and break off. It is with a view to accomplishing the desirable results above noted, in a more perfect degree than has heretofore been possible, that the present invention has been devised.

To this end, then, said invention consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—Figure 1 is a perspective view of a brush embodying my several improvements; Fig. 2 is an end elevation of such brush; and Fig. 3 is a perspective view of several detached strands showing the manner in which they are assembled to com-

pose the tufts that enter into the construction of such brush.

As will be readily evident from an inspection of the figures just described, the brush comprises essentially a back A, in suitable apertures a in which are inserted a plurality of bristle tufts B. The tufts are held in their respective apertures by means of wires b' or like fastening means that pass through the heads of aligned tufts, Fig. 1, on the top side of the back A. These apertures are suitably spaced and disposed depending upon the character of the tufts and the particular use to which the brush is to be put. It is to the form of the component strands of the tufts themselves and to the manner in which the latter are inserted with reference to such form that attention is more particularly desired. These tufts are composed of a number of flat metal strands b doubled over upon themselves and assembled with their flat faces in juxtaposition. The doubled over ends designed for insertion in the apertures a in the back A are pressed tightly against each other, but the free ends naturally more or less bushy or divergent are rendered still more so by being crimped transversely of their flat faces substantially throughout the whole length of such free portions of the strand. The tufts thus composed and assembled are inserted carefully so as to dispose such flat crimped faces of the constituent strands transverse of the proposed direction of movement of the brush when in use. This, where the brush is of oblong form, will ordinarily be transversely of its length. The fastening wires b' it will be observed serve to maintain the tufts in their proper original positions.

By the foregoing construction of brush I attain a much superior and more durable article. By having the flat strands bent or crimped all in the same way and then disposed, when inserted in the brush back, in a definite relation with respect to such manner of bending or crimping, the necessary "body" is given to the brush in the direction of movement of the latter when in use, that is, the strands will support each other in this direction, the movement of one being transmitted to the next adjacent and so on down the entire length of the brush. In this way the strain on the individual strands is very much decreased, as is also the tendency to vibration, owing to the inter-engage-

ment of the longitudinally adjacent faces of the strands. At the same time there is no such interference between laterally adjacent strands, each strand being as free to move, 5 so far as the strands on either side are concerned, as in the ordinary flat wire brush. Thus, a much superior result is obtained over that secured in round wire brushes which I am well aware have been crimped, 10 for in the latter the direction of the crimping with relation to the movement of the brush is wholly a matter of indifference and cannot be controlled. Such brushes accordingly tend to become tangled from the first 15 and from use very quickly become "matted" thus defeating the use of the brush in its proper way at all. A peculiar efficacy is accordingly seen to be attached to the application of crimping to the strands of the flat 20 wire brush which so far as I am aware have never been appreciated nor realized heretofore.

Having thus described my invention in detail that which I particularly point out and 25 distinctly claim is:—

1. As an article of manufacture, a brush comprising a back and a plurality of flat strands inserted therein, said strands having

their flattened faces transversely crimped substantially throughout their length and 30 being disposed with such faces transverse of the proposed direction of movement of the brush in use.

2. As an element in a brush, a tuft consisting of a number of flat metal strands 35 doubled over and assembled with their flat faces in juxtaposition, such faces being transversely crimped substantially throughout the length of the strands.

3. As an article of manufacture, a brush 40 comprising a back, and a plurality of tufts inserted therein, each such tuft consisting of a number of flat metal strands double cover and assembled with their flat faces in juxtaposition, such tufts being mounted with the 45 flattened faces of the strands transverse of the proposed direction of movement of the brush in use, and said strands having their faces transversely crimped substantially throughout the length of the strand. 50

Signed by me this 15th day of November, 1907.

EDWARD E. RICE.
